(57) **CLAIM**

The ornamental design for a articulating level, as shown.

DESCRIPTION

FIG. 1 is a perspective view of an articulating level showing my new design.

FIG. 2 is a right side view thereof.

FIG. 3 is a left side view thereof.

FIG. 4 is a rear view thereof.

FIG. 5 is a front view thereof.

FIG. 6 is a top view thereof.

FIG. 7 is a bottom view thereof.

FIG. 8 is a perspective view of my articulating level of FIG. 1 showing an alternate configuration.

FIG. 9 is a right side view thereof.

FIG. 10 is a left side view thereof.

FIG. 11 is a rear view thereof.

FIG. 12 is a front view thereof.

FIG. 13 is a top view thereof.

FIG. 14 is a bottom view thereof.

FIG. 15 is a perspective view of my articulating level of FIG. 1 showing another alternate configuration.

FIG. 16 is a right side view thereof.

FIG. 17 is a left side view thereof.

FIG. 18 is a rear view thereof.

FIG. 19 is front view thereof.

FIG. 20 is a top view thereof; and,

FIG. 21 is a bottom view thereof.

1 Claim, 10 Drawing Sheets
